UNITED STATES PATENT OFFICE

ERNST BORREGARD, OF GREAT NECK, NEW YORK, ASSIGNOR TO LEO H. FULLER, INC.,
OF LONG ISLAND CITY, NEW YORK, A CORPORATION OF NEW YORK

SCREEN PRINTING MACHINE

Application filed July 13, 1927. Serial No. 205,429.

My invention relates to a machine for producing pictures or designs by the use of color mediums which are substantially paints, and by a process which consists essentially of applying each successive color layer upon the cardboard sheet or other base through permeable portions of a fabric screen, other portions of the screen being rendered impermeable by a coating of shellac, or similar material.

The machine includes as principal features, means for feeding, registering and securing the successive sheets in position for printing or stencilling; means for supporting, raising and lowering the stencil which is usually called a "screen"; means for maintaining a suitable amount of color upon the screen and for automatically wiping the color over the upper face of the screen to produce a proper color imprint through the screen upon the card, and means for properly discharging the card after the stencilling operation.

The machine also includes other novel or improved combinations or arrangements of parts as sufficiently explained in the following detail description of the accompanying drawings, which show one representative embodiment of the invention. After considering this example, skilled persons will understand that many variations may be made, and I contemplate the employment of any structures that are properly within the scope of the appended claims.

Fig. 1 is a side elevation of a complete machine embodying my invention.

Fig. 2 is a plan view.

Fig. 3 is a section at 3—3, Fig. 2, on an enlarged scale.

Fig. 4 is a section at 4—4, Fig. 1, on an enlarged scale.

Fig. 5 is an enlarged detail of a portion of one of the conveyor chains and card feed devices thereon.

Fig. 6 shows the same parts in another operative position, and

Fig. 7 is a section, enlarged, at 7—7, Fig. 2.

The screen proper consists of a sheet of silk of suitable dimensions the margins of which are secured to the edges of a frame so

that the screen fabric overlies one main face of the frame and the inner contour of the frame forms a reservoir for the liquid color. The frames heretofore employed have been simple rectangular frames of wood or other suitable material (not illustrated); the frame illustrated embodies improvements set forth in my co-pending application, Serial No. 272,917, filed April 26th, 1928, now U. S. Patent #1,742,339, dated January 7th, 1930.

The silk screen is first coated all over with a watersize which permeates the screen fabric. After this dries the design is placed upon the inner face of the sized screen by applying shellac coating thereto the areas corresponding to the design being left free and all other areas being filled in with the shellac coating. After the shellac dries the water sizing on the design spaces or areas is washed out, leaving the natural fabric in permeable condition, and producing in effect a screen-stencil for application to the cardboard or other base. Desirably strips of adhesive paper are then placed about the inner contour of the frame, with portions overlapping the margins of the screen, to prevent the liquid color from leaking out between the screen and under faces of the frame members, and this paper stripping may then be shellacked.

The cardboard sheet is then placed on a table, the screen is superposed upon it with suitable simple precautions for proper registration, and a substantial quantity of the liquid color, which is practically a paint, is poured upon the screen, being confined by the inner edges of the frame. A simple hand-operated wiper is then brushed across the upper face of the screen from one end to the other of the frame thus insuring a proper permeation of the stencil design by the color, or practically wiping the color through the stencil spaces and applying it properly to the card. The frame is then lifted, the card removed, another card positioned on the table, the screen replaced and so on. In a multi-color process, to which the method is especially well adapted, the successive cards are placed in racks for drying and a number of stencils are prepared on similar screens, each

corresponding to one color of the complete design, and the cards are successively operated upon with the successive stencils, to produce various highly-decorative "poster" or other designs.

While the described hand process produces multi-color pictures or designs of high quality, it is relatively slow and expensive on account of the time required for placing and removing the sheets, and manipulating the stencil and wiper, and my invention therefore provides a substantially automatic machine, for carrying out by machine operations the described printing or stencilling process.

The machine is built upon or about a main frame see Figs. 1 to 5, which includes legs 20, rectangular side members 21 with suitable cross connection, and brackets 22 extending from the front ends of the side members. A feed table 23 is supported by the brackets 22 and a printing table 24 is located at the top of the main frame.

Card-feed conveyors in the form of chains 25 run from one end of the machine to the other, the upper stretches of the chains being located in slots 25a in the tables, so that their upper faces are flush with the upper table surfaces. At one end each chain passes around a sprocket 26 on a shaft 27 rotatably mounted in bearing-blocks 28, which are adjustably mounted in brackets 22 by means of slots 29 therein and bolts 30 to hold the bearing-blocks in adjusted position. At their other ends the chains pass about sprockets 31 on a shaft 32 mounted in fixed bearings 33.

Each chain carries spaced pushing and gripping devices 34, these devices on the respective chains being aligned in the lateral directions of the machine. As shown in Figs. 5 and 6, each of the devices includes a block 35 which may be one of the chain blocks, provided with a shoulder 36 to engage the card edge. The next adjacent chain block 37 is formed or provided with an arm 38 having near its end a tooth or prong 39 adapted to engage or perforate the card. As the devices 34 pass about the sprocket 26 the relative angular deflection of the blocks 35 and 37 causes the arms and prongs 39 to be in elevated position and when blocks 35 come to a position almost vertically above the sprocket axis, shoulders 36 engage the card edge and begin to advance the card over the table, and immediately thereafter the chains straighten out, blocks 37 coming into line with blocks 35 and the free ends of arms 38 are thus moved downward, pressing the points of prongs 39 upon the card. The prongs do not at this time however necessarily puncture the card, but complete puncturing thereof to cause positive engagement of the card with the feed devices is provided at a point in the further travel of the card, as later explained.

At the front end of the machine (at the

right, Figs. 1 and 2) curved guards 45 are provided to protect the operator from the card feeding devices as they rise above the level of the table in the last part of their travel around the sprockets 26. The guards are provided with openings at 46 to permit the card feed devices to pass onward to the left.

The operator places the cards C to be imprinted successively on the feed table 23, the lateral position of the card being determined by an adjustable gauge 47. The feed devices 34 on the two chains then approach simultaneously and just as they emerge from the openings of the guards 45 they engage and feed the card in the manner above explained.

In each feed movement of the chains the card is carried from the initial position on the feed table to a proper position on the printing table to receive a stencil impression. In this travel the surface of the card is brushed to clean and properly condition it by a cylindrical brush 50 carried by shaft 51 mounted in bearings 52 which are vertically adjustable in brackets 53 located near the rear end of the feed table. The brush is constantly rotated by pulleys and a belt 50a from a main shaft 136 (later referred to), revolving in the direction indicated by the arrow, so that dust, lint etc. are brushed back away from the printing table. The brush is desirably enclosed in a cover or housing 54. Just rearward of the brush, rolls 55 are mounted above the conveyor chains in brackets 56 secured to the brush-housing frame, see Fig. 3.

As the card feed devices 34 pass under rolls 55 the rolls press down the upper members 38 of the feed devices and force the studs or teeth 39 through the card so that the card is then firmly locked in the feed devices. The chains are then simultaneously brought to rest with the card positioned upon the printing table, and accurately registered both in longitudinal and lateral directions by the positive connection of the card to the feed devices and also by positive locking and registering means for the conveyor chains, as later described. After the stencilling or printing operation the chains are again advanced and the stencilled card is ejected on to any convenient receiving device such as a carryoff belt or the table 58, Fig. 1. As the feed devices 34 reach a position directly above shaft 32 and begin to travel around the sprockets 31, the angular deflection of the chain links supporting said device causes the upper members or jaws to open to release the card, and the speed of the chains is such that the card is thrown well onto the table 58 and clear of the chains. At the same time that a card is ejected another one is fed from the feed table to the printing table.

To support and move the screen frame see Figs. 2, 3 and 4 in proper relation to the card feed movements, a rectangular screen-sup-

130

porting frame 60 corresponding to the plan outline of the stencil frame, is connected to brackets 61 which have bearings 62 mounted on a longitudinal shaft 63. The screw studs 5a of the printing frame are passed up through corresponding apertures in frame 60, and nuts 64 are applied to secure the screen frame in position. The side members 65 of frame 60, and angle strips 66 having 10 vertical flanges 67, form in effect upward extensions of the inner contour of the screen frame and provide a reservoir to hold any desired amount of liquid color, with walls deep enough to avoid splashing of the color.

15 The screen frame is raised, by slight oscillation of frame 60 about shaft 63, during movement of each card to printing position, and after the card has been positioned the printing frame is lowered to bring the screen close 20 to but not in actual contact with the upper face of the card. Means for automatically moving the frame 60 is described hereafter.

Automatically actuated scraping or color distributing means is provided to properly 25 force or brush the color through the permeable portions of the screen representing the pattern, and this means is also devised to force the screen downward the slight distance required to make contact with the upper face 30 of the card as the rubbing or scraping blade passes over the upper face of the screen, immersed in the color thereon. For this purpose carriage guides 70 are secured above frame 60, at either side thereof. A scraper-carriage 72 extending across the machine is 35 mounted to reciprocate in straight guide channels 73 in the inner faces of the members 70. A driving chain 74 has its ends connected to forward and rear portions of the carriage 40 as at 75. These connections may be in the form of brackets 76 to which the chains are connected and which in turn are connected to a vertical plate 77 of the carriage by means of slots 78 therein and studs or screws 79 on 45 the brackets passing through the slots. A spring 80 tensioned between the brackets may serve to take up slack in chain 74. The inward stretch of the chain, in line with the brackets 76, passes around idler pulleys 80 mounted on vertical stud shafts 81. Lateral 50 stretches of the chain pass about a pulley 82 and a sprocket 83 carried by short shafts 84 and 85 mounted for rotation in brackets 86 to complete the chain circuit, which includes 55 the outer longitudinal stretch 87. Sprocket 83 is the driver for chain 74, and for this purpose is connected to a bevel gear 88 which engages another bevel gear 89 revolvably 60 mounted on shaft 63. Gear 89 is driven by connections later described, and since it is mounted on the pivot axis of frame 60 the chain 74 may be driven to and fro for the reciprocation of the scraper carriage without 65 any interference with the driving connec-

tions being caused by the tilting movement of the frame.

A transverse shaft 90 is mounted for oscillation in the end members of the scraper carriage. A scraper body 90a is detachably connected to short sleeves 90b which are free to rotate upon shaft 90. The sleeves 90b have lugs 90c projecting at opposite sides of the shaft. Other sleeves 90d are rigidly secured on the shaft and these sleeves have oppositely-projecting lugs 90c, and set screws 90f pass through these lugs and engage lugs 90c of sleeves 90b; so that by rotation of the screws the angular position of the sleeves 90b and of the scraper block connected to them, in relation to the shaft, may be regulated to properly position the scrapers. The sleeves 90b have downwardly projecting slugs 90g, and set screws 90h project from these lugs through the scraper block 90a and the latter is detachably secured in position by thumb nuts 90k engaging the screws. Provision is thus made for easily and quickly removing the scraper block and scrapers, as for example when a new screen is placed in the machine for use with another color. The scraper strips 91 desirably consist of substantially stiff but flexible material such as rubber composition or canvas with rubber vulcanized thereon, and they are detachably secured to 95 angular faces of the block 90a by plates 92 and thumb nuts 93.

Two scraper blades are provided because it is desirable to scrape the color across the screen with a dragging rather than a vertical or pushing action; that is, the active scraper blade should be inclined rearwardly downward as shown in Fig. 3, in which the carriage is moving to the right and the active (lower) scraper 91 is in contact with the screen and is therefore inclined in the manner just stated, which gives a smoother and more positive contact with the screen and more effective wiping action of the color upon and through the screen design, than if the blade were held vertical or inclined in a direction opposite to that shown. This also provides for maintaining the proper distribution of the color in the reservoir provided by the screen frame and the supporting frame 60. Thus if a single scraper were used it would tend to push ahead of it a great part of the color in the reservoir and upon return movement the color would remain behind the blade instead of being in front of it or more uniformly distributed over the screen. By the present arrangement however when the lower blade of Fig. 3 reaches the end of its travel near the right hand end of the frame, it is raised and the other scraper lowered and at the same time the color which was previously trapped ahead of the first named blade is released and is then in position to be pushed ahead of the blade which is about to make a return movement (to the left as viewed in Fig. 3). For 100 105 110 115 120 125

the purpose of properly oscillating shaft 90 to make one of the wiper blades operative for each direction of carriage travel, an arm 100 is secured to shaft 90 near each end thereof, 5 and these arms are provided with outwardly-projecting cam rolls 101 to cooperate with guide-channel and cam devices provided on the inner faces of the guide structures 70. Thus on the inner face of each guide structure 10 is an upper channel 102 and a lower channel 103 separated by a central flange or rail 104. At the forward end this rail is bevelled or tapered to form a descending cam face 105 and at its rear end is bevelled to 15 form an ascending cam face 106. At the forward end of the lower channel 103 is a rising or upwardly directed cam member 107 leading to a horizontal rail member or flange 108 elevated slightly above the level of the 20 lower point of cam 105. At the rear end of the upper channel 102 is a descending or downwardly inclined cam member 109. In the position shown in Fig. 3 in which the scraper carriage has started to move forward, 25 the cam rolls 101 on arms 100 are located in the lower channels 103, thus positioning the rock shaft 90 as shown, to hold the rearward scraper blade 91 in contact with the screen to properly wipe the color over and through 30 the screen for the production of a proper imprint upon the card as the carriage moves forward. Before the carriage reaches its foremost position rolls 101 ride up on the cam faces 107 and in the final travel of the carriage are located on the horizontal flanges 108. The shaft 90 is thus oscillated to partly 35 raise the rearward scraper and lower the forward scraper 91 and thus relieve the screen of scraper-pressure. Shaft 90 has a fairly 40 tight fit in its bearings and moreover there is no force tending to accidentally tilt the shaft so that in the beginning of its rearward movement (toward the left in Fig. 3) the rolls 101 pass over the space between the cam 45 faces 107 and 105, and then ride up on the cam faces 105 and enter the upper channels 102, and the forward scraper blade 91 is thereupon positioned for proper action in the rearward movement of the carriage. As the carriage 50 approaches its rearward position the rolls 101 strike the downwardly inclined cam faces 109 to partly raise the forward scraper blade and partly lower the rear scraper blade, and then in the forward movement of the carriage the rolls encounter the downwardly inclined cam faces 106 which further tilt the scrapers to the position shown in Fig. 3, where the rear scraper is in action during the forward travel of the carriage.

The carriage driving mechanism is so arranged that after a card is positioned on the printing table and the screen frame is lowered the scraper carriage moves in one direction to apply the color to the card, then rests while the screen is raised, the printed card

ejected and a fresh one positioned on the printing table; the screen is then lowered and the scraper moves in the other direction to properly apply the color, and so on.

Desirably shock absorbing means is provided to yieldably check the carriage at either end of its stroke, consisting of plungers 110 mounted in guides 111 at either end of the carriage with springs 112 compressed between the heads of the plungers. Lugs 113 75 are provided at opposite ends of the frame in position to be engaged by the plungers whereupon the springs are compressed and the carriage is yieldingly checked.

While not necessary in all cases, it is desirable to provide additional means for properly and positively holding the cards in printing position, and prevent the screen from raising the card as the former rises. Suction means is desirably employed for this 80 purpose and comprises apertures or channels 113 located in any desired positions in the upper face of the printing table to exhaust air from under the lower face of the card and thus hold it flat and smooth upon the table by atmospheric pressure acting upon the upper face of the card. The various apertures or channels 113 are connected by ducts formed on or in the table and these are connected to pipes 114, and all the pipes 95 are connected to one conduit 115 leading to an exhaust pump 116.

As a simple means of releasing the card from the vacuum pull or suction effect after the printing operation, a cylindrical fitting 100 117 is interposed in the air conduit 115, the upper end of this fitting being formed as an annular valve seat 118 to cooperate with a valve 119. This valve is connected to a rocker 120 pivoted on a fixed frame member, one arm of the rocker being connected to a spring 121 which urges the valve to open position. The rocker arm to which the valve is connected has a toe 122 to cooperate with a latch member 123 pivoted at 124 to the tilting frame, and urged to the left as viewed in Fig. 1 by a spring 125. The latch has a notch 126 terminating in upper and lower horizontal faces 127 and 128, to cooperate with the toe 122, and a lower bevelled face 129. 115 Whenever the screen-supporting frame 60 is moved downward, just after a card is positioned on the printing table, the bevelled face 129 of latch 123 slides over the end of the toe 122, and thereafter the latch springs back 120 to vertical position and its upper shoulder 127 depresses the toe 122 and closes the valve 119, thus closing the suction pipe line, and air is therefore exhausted from the under face of the card to hold it in proper flat condition 125 for printing. After printing, in the upward movement of the screen supporting frame, the lower shoulder 128 of latch 123 engages toe 122 and opens the valve, thus destroying the suction in the air conduit and freeing the 130

card, which is then moved away by the conveyor chains.

The driving means or connections may vary greatly, but in the preferred example 5 shown they comprise the following:

A motor 130 located in any convenient position near the machine has its shaft 131 connected by a belt 132 to exhauster 116, which may be continuously driven, when the 10 suction effect is controlled by such means as above described. The motor shaft is also connected by suitable reduction gearing 133, sprockets and a chain 134 to a sleeve 135 rev- olubly mounted on a transverse shaft 136 15 which is the main driving shaft of the machine proper. The sleeve is releasably connected to shaft 136 by a clutch 137 having a suitable shifter 138, and a shifting linkage 139, connected to a lever 140, convenient to 20 the operator. On one end of the drive shaft is a hand wheel 141 for turning the machine over by hand in making adjustments, etc.

Near the other end of shaft 136 is a sprocket 141 connected by a chain 142 to a sprocket 25 143 on a shaft 144. The chain is adjusted by an idler 145. On one end of shaft 144 is a cam body 146 having in one face a cam groove 147 in which is located a cam roll 148 carried by the lower end of a plunger 30 149 mounted for reciprocation in guides 150. The cam plunger may be arranged to positively elevate the screen frame, but in a preferred arrangement as shown the frame is actually moved upward by spring plungers 35 151, Fig. 1, mounted in cylinders 152 secured to one of the frame side members 21, these plungers being urged upward by springs 153 within the cylinders. The upper ends of the spring plungers engage lugs 40 154 connected to the screen-supporting frame. The upper end of the cam-actuated plunger 149 is connected to the screen supporting frame by a swinging link 155, adapted to enter a slot 156 formed in a lug 157 projecting from the frame. The link has a pin 45 158 which engages in half-round notches 159 in the upper face of the lug at either side of the slot. When the link is in active position as shown, after a card has been positioned on the table for printing, the cam slot in cam body 146 acts on roller 148 and the plunger to pull the latter down, and so pull 50 55 down the screen frame to active position; and after the scraper carriage has been traversed over the screen to apply the color in the manner above described the cam permits the plunger and frame to rise under the impulse of the spring plungers 151, 60 65 whereafter the printed card is carried away and a new one positioned, and so on.

In order to permit the screen frame to be raised higher than it normally rises in the operation of the machine, for example in 65 order to remove the screen and replace it

with another one, the screen-supporting frame may be released from its controlling plunger by merely swinging link 155 forward; and the parts are easily restored to normal position by pulling the frame down 70 and re-inserting the swinging link in its slot.

For driving the card conveyor chains in properly timed relation to other parts of the mechanism, shaft 144 is provided with a 75 gear 160 engaging a gear 161 on another transverse shaft 162. This shaft is arranged to drive the conveyor chain driving shaft 32 by any suitable means such as a Geneva mechanism and multiplying gearing, for 80 the purpose of securing the proper conveyor chain travel alternating with rests for the performance of other operations particularly the movement of the screen frame and the traverse of the scraper carriage. Specifically, in the present example shaft 162 has thereon the usual Geneva stud or driving roll 163 carried by an arm 164, and a stop-disk to cooperate with a four-part Geneva wheel 165 on another transverse shaft 166. 85 This Geneva wheel is arranged to rotate freely on its shaft and is held in an axially fixed position although the shaft is mounted for axial movement for a purpose later referred to. Connected to revolve with the 90 Geneva wheel is a large gear 167, engaging a pinion 168 on conveyor chain drive shaft 32. The gear ratio is such that in each quarter turn of the Geneva wheel, produced by one revolution of each of shafts 144 and 162, the conveyor drive shaft 32 is rotated a sufficient number of turns to advance the conveyor chains a proper distance for one 95 card-feeding operation.

Since the parts leading up to the conveyor 100 drive shaft, and the conveyor system proper including the chains and sprockets, have considerable inertia, it is desirable to provide means for checking their advance at the end of the feed movement. For this purpose a brake drum 170 is secured on conveyor drive shaft 32, cooperating with brake shoes 171 urged to braking position by a spring 173, and retracted by a cam 174 connected to a lever 175, which is provided with a cam roll 176 running on the periphery of a cam 177 fixed on shaft 162. The notch 178 in cam 177 is dimensioned and positioned so that at the end of the proper feed travel of the conveyor chains, roll 176 drops into the cam notch or depression, and the brake is applied by its spring 173 to bring the conveyor system to rest with the desired promptness, and shortly thereafter, and before the next propulsion of the conveyor chains, the cam roll is moved to the circular periphery of the cam, and the brake is released, ready for the next conveyor action. 115 120 125

For the reciprocation of the scraper car- 130

riage, shaft 162 has near the end opposite to the Geneva mechanism, a segment gear 180 cooperating with a pinion 181 having a stop-sector 182 to cooperate with the smooth semi-circular periphery of gear 180. The face of pinion 181 is broad enough to remain in operative contact with gear 180 at all times although the pinion is shifted axially in the shifting movement of shaft 166 referred to 10 shortly below. Also operatively fixed on shaft 166 are bevel gears 183 and 184, spaced a proper distance for alternate engagement with a bevel pinion 185 on a horizontal shaft 186 which is also provided with a sprocket 15 187 connected by a chain 188 to a sprocket 189 secured to the hub of bevel gear 89 mentioned earlier above, which gear is revolvably mounted on the longitudinal shaft 63 and has a driving connection also above explained to 20 the carriage driving chain 74. Near the center of shaft 166 cams 200 are secured in spaced relation at either side of cam fingers 201 carried by a fixed yoke 202. The driving mechanism including gear 120, pinion 181, and 25 bevel gears 183 and 184, are so proportioned that at each revolution of shaft 162, corresponding to one feed movement of the conveyor chains, the scraper carriage drive chain is driven in one direction or the other to provide for the full travel of the carriage in the 30 corresponding direction while the toothed part of gear 180 rotates pinion 181, and then the pinion and the driving mechanism leading from it to the scraper carriage is held stationary during the next half rotation of gear 35 180, while its semi-circular peripheral portion is engaged with the stop sector of pinion 181. Cams 200 are so proportioned and arranged that near the end of a rotative movement of pinion 181 and its shaft, or at the 40 beginning of the next rotary movement, the shaft is shifted longitudinally, first one way and then the other, to bring gears 183 and 184 alternately in engagement with opposite 45 sides of bevel pinion 185. Thus the scraper carriage driving system from pinion 181 to the scraper carriage is alternately driven in opposite directions to provide the desired full travel of the scraper carriage in one direction 50 and then after the positioning of a fresh card and of the screen frame in relation thereto, for traverse of the scraper carriage in the other direction, and so on.

It is desirable in some cases to provide additional means for insuring accurate registration of the card feed mechanism by the accurate positioning of the chains to which the card is positively secured in the manner above described. This is especially desirable because these machines are usually employed in a multi-color process where the same card has to be successively positioned in the same or different similar machines, the number of these positionings corresponding to the number of colors in the design, and very accurate

registration at each operation is therefore essential. For this purpose a stop disk 210 is secured on a conveyor chain drive shaft 32 in a convenient position, near one of the frame side members 21, and a tapered stop socket or notch 211 is provided in the periphery of the disk. A plunger 212 is provided to cooperate with the notch, this plunger having a tapered end and being reciprocably mounted in a socket 213 secured to the frame. The lower 75 end of the plunger is connected to a bell crank fulcrumed on shaft 166, and one arm of the bell crank is provided with a cam roll 215 cooperating with a cam 216 on shaft 162. The cam is dimensioned and positioned on its 80 shaft so that just as the conveyor drive shaft 32 is being brought to rest by cessation of the driving impulse, and the application of its brake 171, at the end of a card feed action, the rise of cam 216 operates the bell crank 214 and forces the tapered end of plunger 212 into the stop socket, and the cooperating tapered formation of the socket and plunger therefore produces an extremely accurate angular 85 positioning of the stop disk, the drive shaft 90 and the conveyor chains, thus accurately positioning or registering the card for printing, regardless of any play or backlash in the gearing leading to the conveyor drive shaft 95

By the described arrangement of the screen supporting frame and other parts carried by it, and especially the pivotal connection of this frame to shaft 63 located at one side of the machine, when latch 155 is disconnected in the manner above described, the supporting frame may be swung to completely upright position and will then be located vertically at one side of the machine, leaving the printing table entirely free and clear so that it can be easily and conveniently cleaned. In ordinary operation the total vertical movement (or swinging movement of the frame about its axis 63) is only about 2", this slight motion being made possible by the employment 105 of automatic card feeding means; and the total speed of the machine, or the total output, is correspondingly increased.

I claim:

1. In a screen printing machine comprising a feed table, a printing table aligned therewith, means for feeding successive cards from the feed table to the printing table and away from the printing table, a screen-supporting frame movably mounted above the printing table, and means, for moving the frame vertically, the combination therewith of a wiper carriage mounted for reciprocation above the screen, two flexible wipers thereon located in different oblique vertical planes, means for reciprocating the wiper carriage, cam means carried by said wiper carriage and a guide extending along said printing table co-acting with said cam means for moving said wiper carriage to thereby 115

- move said wipers alternately to and from active position whereby one wiper is in wiping contact with the screen surface while the carriage moves in one direction the other wiper is in active position while the carriage moves in the other direction. 5
2. A screen printing machine comprising a printing table, a feed table, a printing table aligned therewith, means for feeding successive cards from the feed table to the printing table and away from the printing table, a screen-supporting frame movably mounted above the printing table, means for moving the frame vertically, and means for cleaning 10 the successive cards during their movement toward the printing table. 15
3. In a screen printing machine, a printing table, a screen supporting frame pivotally mounted at one side of the table, means yieldably supporting the other side of the frame, means for moving the frame vertically, said means comprising a cam and a vertical plunger, and means carried by said plunger for quickly releasing the connection between 20 said plunger and the frame. 25
4. In a screen printing machine, a printing table, a screen supporting frame pivotally mounted at one side of the table, a wiper carriage reciprocating in guides on the frame, a 30 drive chain for the carriage supported to move in a substantially horizontal rectilinear path, means for driving the chain alternately in opposite directions, and a yielding connection between the chain and the carriage. 35
5. In a screen printing machine, a printing table, a screen supporting frame, a wiper carriage, a wiper shaft mounted for oscillation in the carriage, means for oscillating the shaft, wipers mounted on the shaft, and means for adjusting their angular position 40 in relation to the shaft. 45
6. In a screen printing machine, a printing table, a screen supporting frame, a wiper carriage, wiper means rotatably supported by said wiper carriage, means for feeding in a certain direction cards to said screen supporting frame in pre-determined position over said printing table, means secured at a side of said printing table transverse 50 to said certain direction for supporting said screen supporting frame relative to said printing table, and means independent of said card feeding means for holding the fed card in position on said printing table 55 during the period of operation of said wiper means. 60
7. In a screen printing machine, a printing table, a screen supporting frame, a wiper carriage, wiper means rotatably supported by said wiper carriage, means for feeding in a certain direction cards to said screen supporting frame in pre-determined position over said printing table, means secured at a side of said printing table transverse to said 65 certain direction for jointly supporting said
- screen supporting frame and said wiper carriage relative to said printing table, and means independent of said card feeding means for holding the fed card in position on said printing table during the period of 70 operation of said wiper means. 75
8. A screen printing machine comprising a printing table, a screen-supporting frame above the table, means for moving the frame vertically in relation to the table, a feed table, means for feeding successive cards from the feed table to the printing table and away from the printing table, a brake for checking the movement of said card feeding means, and means for applying the brake 80 substantially at the end of each conveyor movement. 85
9. In a screen printing machine having a printing table, a screen supporting frame, means for operating the frame, a card conveyor for advancing cards successively to printing position on the table, and movement limiting means for the conveyor comprising a member revolving in accordance with conveyor movements and a plunger co-operating with a notch in said member, and means for retracting the plunger. 90
- In testimony whereof I have signed this specification this 1st day of July, 1927.
- ERNST BORREGARD. 95
